VALVE SHIELD

Filed Sept. 9, 1922

2 Sheets-Sheet 2

UNITED STATES PATENT OFFICE.

THOMAS R. BURKE, OF WASHINGTON, DISTRICT OF COLUMBIA.

VALVE SHIELD.

Application filed September 9, 1922. Serial No. 587,173.

To all whom it may concern:

Be it known that I, THOMAS R. BURKE, a citizen of the United States, residing at Washington, in the District of Columbia, 5 have invented certain new and useful Improvements in Valve Shields, of which the following is a specification.

This invention relates to an improved flushing valve equipment. The flushing 10 valves of the direct type, or in other words, those which are connected directly with the water supply main and are employed in connection with various plumbing installations, are usually made of nickel plated 15 or polished brass or bronze and are, therefore, subject to corrosion which renders them both unsightly and insanitary. Furthermore, such valves are difficult to cleanse and keep in a cleansed condition due to 20 the readiness with which they corrode, and their general appearance is usually not in keeping with the other plumbing fixtures. These fixtures are ordinarily furnished in 25 white water-impervious materials which are not readily subject to soiling and which are adapted to be readily cleansed, and it is, therefore, one of the primary objects of the present invention to provide, as an equipment of a valve of the general type above- 30 mentioned, an encasing shield or shell which will completely enclose the valve, its inlet and outlet connections, and more or less of its otherwise exposed controlling parts and which may be finished with a surface 35 in harmony with the surface finish of the plumbing fixtures in conjunction with which the flushing valve is employed. In this manner not only are the valve fittings of a plumbing fixture made to harmonize with the finish of the fixture, but also the said 40 valve fittings may be readily kept in a clean and sanitary condition with no more labor than that involved in cleaning the fixtures themselves.

Another important object of the invention 45 is to provide an encasing shield for the valve fittings which will comprise sections so formed and constructed as to adapt them to be readily and conveniently assembled about the flushing valve, its inlet and outlet connections, and more or less of its controlling parts, and firmly secured in place and yet in such a manner and by such means to permit of the removal or displace-

ment of the sections whenever it is necessary to gain access to the valve and its fittings.

Another object of the invention is to provide an encasing shield constructed on such principles that the invention may find embodiment in shields adapted for installation upon flushing valves of various shapes and dimensions and installed in various ways, the invention being particularly concerned, however, with flushing valves of the direct type but regardless of direction of extent of the inlet and outlet connections or the character or arrangement of the controlling handle or other parts.

In the accompanying drawings: 70

Figure 1 is a side elevation of the encasing shield embodying the invention installed in connection with a flushing valve of the direct type and its associated plumbing fixture; 75

Fig. 2 is a plan view of the structure shown in Figure 1;

Fig. 3 is a vertical front to rear sectional view through the shield installed, the valve and its fittings being shown in elevation; 80

Fig. 4 is a vertical transverse sectional view on the line 4—4 of Fig. 3 looking in the direction indicated by the arrows and with the inlet connection of the valve omitted;

Fig. 5 is a group perspective view illustrating the component parts or sections of the shield disassembled.

In the drawings, the numeral 1 indicates in general the plumbing fixture which is to be flushed with water supplied through the medium of the flushing valve which is indicated in general by the numeral 2 and which valve is, as previously stated, of the direct type. The numeral 3 indicates the wall in juxtaposition to which the fixture 90 95 1 is installed and through which connection is made between the valve and the water supply pipe (not shown). The valve 2 comprises the usual casing 4 having the usual inlet coupling 5 which embodies the coupling proper indicated by the numeral 6, the short pipe section 7 which is fitted to the valve casing and to which the coupling is connected, and the usual collar 8 which is disposed about the usual branch pipe leading from the coupling to the water supply pipe, this collar seating directly against the surface of the wall 3. In the drawings the 100 105

valve 2 is illustrated as connected with the water supply by a coupling which leads directly rearwardly from the casing of the valve but it will be understood that the inlet coupling might be directed laterally from the valve casing in either direction or in fact in any other direction without necessitating any deviation from the principles of the invention, the only changes required being those concerned with the form or shape of the shield sections. The outlet coupling for the valve which may lead into the top, rear, or either side of the bowl, is indicated by the numeral 9 and is of the ordinary construction, including a pipe section or nipple 10 which may be of greater or less length and straight, curved, or angular, depending upon the manner in which the valve is installed. The coupling 9 includes, however, the usual collar 11 which is disposed about its lower end where it joins the fixture 1 and which collar bears flat upon the upper surface of the fixture and is preferably of the rounded form shown particularly in Fig. 3 of the drawings. The casing of the valve 2 is closed at its top by a cap indicated by the numeral 12 and ordinarily a nut 13 will be found, in such valves, associated with the valve casing at the top of the cap 12. The operating handle for the valve is indicated by the numeral 14 and the said handle may extend laterally as in the present instance, or in any other direction from the valve casing.

The shield embodying the invention comprises two body sections indicated one by the numeral 15 and the other by the numeral 16, a cap section which is indicated by the numeral 17, and a thimble indicated by the numeral 18. The body sections 15 and 16 are substantially of counterpart form and construction and each embodies an approximately semi-cylindrical body portion 19, which at one or more points may be outwardly bulged or otherwise shaped to conform to the contour of the valve casing 4 and the elements comprising the outlet coupling 9. For example, in the particular embodiment of the invention illustrated in the drawings, the body 19 of each section may be formed with a bulge 20 extending circumferentially thereof to accommodate a nut 21 which constitutes one element of the coupling 9, and the upper portion of the body may be bulged as indicated by the numeral 22 so as to accommodate the larger upper portion of the valve casing. The cap 12 of the valve casing will ordinarily provide a shoulder, and in such event the upper end of the body of each of the sections 15 and 16 will preferably be provided with an outstanding flange 23 designed to seat beneath the shoulder provided by the under side of the cap 12, as best shown in Fig. 3 of the drawings. The body 19 of each of the

body sections 15 and 16 is provided at its upper end with a substantially right angular extension indicated by the numeral 24 and this extension is of substantially cylindrical contour and its wall extends through an arc of approximately 90°. The extensions 24 at their inner ends form juncture with the respective bodies 19 in such manner that when the sections 15 and 16 are disposed against opposite sides of the valve casing and its couplings, the bodies 19 will fit about the said valve casing and the upper portion of the outlet coupling 9, and the extensions 24 will fit about the opposite sides of the lower portion of the coupling 5 considered as a unit. The extensions 24 will, as in the instance of the bodies 19, be made of a contour to conform more or less closely to the contour of the coupling 5 and, where the said coupling embodies a cut off valve such as the one indicated in the drawings by the numeral 25, the said extensions 24 will be bulged or otherwise formed as indicated by the numeral 26, to accommodate the casing of the said valve. Of course, in assembling the sections 15 and 16 about the flushing valve and its coupling, the edges of the sections will meet except, of course, the upper edges, which latter will extend along the opposite sides of the valve and inlet coupling and, from the inner ends of the flanges 23, will be curved downwardly, as indicated by the numeral 27, and thence extended in a horizontal plane, as indicated by the numeral 28. When the sections 15 and 16 are fitted into place, the ends of the extensions 24, which are remote from the bodies 19 of the sections, will, if properly fitted, abut against the surface of the wall 3 and more or less closely surround the collar 8.

In order to hold the sections 15 and 16 in their assembled relation it is preferable that the sections be provided in the angle between their bodies 19 and extensions 24 with outstanding ears 29 provided with openings 30 receiving the tubular body 31 of a socket bolt indicated by the numeral 32, the head 33 of the bolt bearing against the outer side of one of the ears, and the head 34 of a binding screw 35, which is fitted into the socket 31, bearing against the outer side of the other ear 29, thus providing an inconspicuous and yet secure connection between the body sections 15 and 16. In order to accommodate the mounting for the operating handle 14, one of the sections, as for example, the section 15, in the specific embodiment illustrated, is provided upon its body 19 with an outwardly projecting sleeve portion 36, the sleeve being designed to fit more or less closely about the said mounting for the operating handle when the section 15 or 16, as the case may be, is fitted into place, it being understood that the sleeve 36 may

be provided upon either of said sections and at any proper point of location depending upon the type of valve.

The thimble 18 preferably comprises two counterpart sections which are indicated by the numeral 37, and each of which is formed to fit substantially half way about the lower portion of the coupling 9, including the collar 11, the lower portion of each section 37 being preferably bulged as at 38, for this purpose. The sections 37 are adapted to be secured together by providing ears 39 at their rear sides through which a clamping bolt 40, of the same type as the bolt 32, is secured, as shown in Fig. 3. The upper portions of the sections 37 are of semi-cylindrical form so that when the sections are fitted together a tubular shell will be provided surrounding the nipple 10 of the coupling 9, and this tubular shell is received at its upper portion within the lower portion of the shell provided by the meeting body sections 15 and 16, the lower ends of these sections being preferably chamfered, as indicated at 41, so as to provide a smooth union between the parts and to give the impression of an integral or one-piece structure, so far as is possible.

The cap section 17 comprises a substantially cylindrical body portion 42 provided with a dome-like bulge 43 at its forward end having a depending approximately circular flange 44 which is designed to extend about the lower portion of the cap 12 of the valve casing, the bulge 43 being designed to seat over the upper side of the said cap and over the nut 13. The said bulge 43 is provided centrally in its top with an opening 45 through which a securing screw 46 is fitted, the said screw being threaded into the upper side of the nut 13. The flange 44 extends about the margin of the outstanding flanges 23 of the sections 15 and 16 and conceals these edges from view. If desired the flange 44 may be provided at its forward side with a socket 47 receiving a buffer block 48 which will take the place of the ordinary seat buffer employed upon the valve. The cap section 17 is designed to be fitted over the upper side of the valve and its coupling 5, and at its lower margin it is preferably provided with an outwardly offset depending flange 49 which fits over the upper edges of the extensions 24 of the sections 15 and 16 as best shown in Fig. 4 of the drawings. While the cap sections 17 is of a more or less semi-cylindrical form it will, of course, be made of a contour to conform more or less closely to the valve casing and its fitting. For example, if the cut off valve 25 embodies an upstanding or projecting part, the section 17 may be provided with a correspondingly located bulge 50 to accommodate said parts. It will now be evident that when the body sections 15 and 16 are assem-

bled about the valve and its fittings, the lower ends of the said sections will encompass the tubular portion 37 of the thimble 18, and the cap section 17 will fit down over the upper portions of the said sections 15 and 16 and their extensions 24 thus holding these parts against separation. The securing screw 46 will, of course, hold the cap section 17 firmly and securely in place upon the valve and therefore all of the parts comprising the assemblage will be securely held against displacement.

In practice the sections comprising the thimble 18 will be made in various lengths or, in other words, with their tubular shell portions 37 of various lengths so as to adapt the shield as a whole to be applied to valves in which the length of the outlet coupling 9 may vary considerably.

From the foregoing description of the invention it will be evident that the several sections of the shield as well as the thimble 18, may be made of enameled material or material finished or surfaced in any other manner desired and in conformity with the finish of the plumbing fixture in connection with the flushing valve of which the shield is employed. Also the thimble 18 serves not only as a means for preventing separation of the lower ends of the sections 15 and 16 but it constitutes likewise a means for concealing the lower ends of the said sections and imparts a more finished appearance to the lower portion of the shield.

It will probably be found desirable to provide the sections 15, 16 and 17 with a lining 52 of felt or some similar cushioning and heat insulating material. This lining will partially eliminate or to a great extent muffle the sound which is created when the valve is in operation and will likewise serve to prevent direct contact between the metallic parts comprising the valve and the shield which would probably occasion a rattling noise in the event of any slight looseness between the sections of the shield; and, because of its heat insulating property it will prevent the formation of moisture of condensation on the exterior surfaces of the valve parts which would otherwise be liable to occur through the difference in temperature of the water flowing through the valve and the room temperature and result in corrosion of the metallic parts.

Having thus described the invention, what is claimed as new is:

1. A valve shield for installation upon a flushing valve having an outlet coupling, comprising sections to be fitted about the said coupling in matched relation, and a cap section to be fitted to the valve casing and formed to engage the first-mentioned sections in a manner to maintain the same assembled.

2. A valve shield for installation upon a

flushing valve having an outlet coupling comprising sections to be fitted about the said coupling in matched relation, and a cap section to be fitted to the valve casing and having a portion to encompass the mating first-mentioned sections in a manner to maintain the same assembled.

5. A valve shield for installation upon a flushing valve having an outlet coupling comprising sections to be fitted about the said coupling in matched relation, a cap section to be fitted to the valve casing and having a portion to encompass the mating first-mentioned sections in a manner to maintain the same assembled, and means associated with the cap section for coaction with part of the valve to maintain the said cap section in fixed relation to the valve.

6. A valve shield for installation upon a flushing valve having an inlet and an outlet coupling connected with its casing, comprising sections to be fitted about one of said couplings and the valve casing in matched relation, said sections having extensions, and a cap section to be fitted to the valve casing and engage the first-mentioned sections in a manner to maintain the same assembled, the said cap section having an extension for coaction with the first-mentioned extensions to enclose the said inlet coupling.

7. A valve shield for installation upon a flushing valve having an inlet and an outlet coupling connected with its casing, comprising sections to be fitted about one of said couplings and the valve casing in matched relation, said sections having extensions, a cap section to be fitted to the valve casing and engage the first-mentioned sections in a manner to maintain the same assembled, the said cap section having an extension for coaction with the first-mentioned extensions to enclose the said inlet coupling, and means for maintaining the cap section fixed with relation to the valve casing and thereby maintain the other said sections likewise in assembled relation.

8. A valve shield for installation upon a flushing valve having an inlet coupling and an outlet coupling, comprising sections to be fitted about the casing of the valve and the outlet coupling in matched relation, said sections having extensions to fit about the under side of the inlet coupling, and a cap section for assemblage with the first-mentioned sections and having an extension for coaction with the first-mentioned extensions, the said cap section being designed to fit the valve casing and its extension to fit the inlet coupling, the said cap section having a flange extending about the upper margins of the first-mentioned sections whereby to maintain the said first-mentioned sections in assembled relation.

9. A valve shield for installation upon a flushing valve having an inlet coupling and

an outlet coupling, comprising sections to be fitted about the casing of the valve and the outlet coupling in matched relation, said sections having extensions to fit about the under side of the inlet coupling, a cap section for assemblage with the first-mentioned sections and having an extension for coaction with the first-mentioned extensions, the said cap section being designed to fit the valve casing and its extension to fit the inlet coupling, the said cap section having a flange extending about the upper margins of the first-mentioned sections whereby to maintain the said first-mentioned sections in assembled relation, and a securing element associated with the cap section for coaction with a part of the valve for maintaining the cap section fixed with relation to the valve casing.

10. The combination with a plumbing fixture and a flushing valve having an outlet coupling secured to the fixture, of a shield for the valve and its coupling comprising sections assembled about a portion of the casing of the valve and about the said coupling in matched relation and enclosing said parts, a thimble telescopically fitting the lower ends of the sections, and a cap section fitted to the other portion of the valve casing and enclosing the same and so engaging the upper ends of the first-mentioned sections as to maintain them in assembled relation.

11. The combination with a plumbing fixture and a flushing valve having an outlet coupling secured to the fixture, of a shield for the valve and its coupling comprising sections assembled about a portion of the casing of the valve and about the said coupling in matched relation and enclosing said parts, a thimble telescopically fitting the lower ends of the sections, a cap section fitted to the other portion of the said casing and enclosing the same and provided with a part encompassing the upper ends of the assembled first-mentioned sections and maintaining them in assembled relation, and a securing element associated with the cap section for coaction with a fixed part of the valve whereby to maintain the cap section fixed with relation to the valve casing.

12. A valve shield comprising sections to be fitted together in matched relation about certain portions of the valve to be encased and a third section for encasing the remaining portion of the valve and having means for coaction with the first-mentioned sections to maintain all of said sections in assembled relation.

13. A shield for valves comprising sections to be assembled about the valve to enclose the same, and a lining of a yieldable heat insulating material within said sections.

12. A valve shield for installation upon a flushing valve having an inlet and an outlet coupling connected with its casing, comprising sections to be fitted about one of said 5 couplings and the valve casing in matched relation, said sections having extensions to fit the under side of one of said couplings, the said sections having ears at their meeting edges, a securing element fastened 10 through said ears, and a cap section fitted to the valve casing and to the upper side of the last-mentioned coupling, the said cap section engaging the first-mentioned sections in a manner to maintain the same assem- 15 bled.

13. A valve shield for installation upon a flushing valve having an inlet and an outlet coupling connected with its casing, com-

prising sections to be fitted about one of said 20 couplings and the valve casing in matched relation, said sections having extensions to fit the under side of one of said couplings, the said sections having ears at their meeting edges, a securing element fastened 25 through said ears, and a cap section fitted to the valve casing and to the upper side of the last-mentioned coupling, the said cap section engaging the first-mentioned sections in a manner to maintain the same assembled, 30 and means for maintaining the cap section fixed with relation to the valve casing to thereby maintain the other said sections likewise in assembled relation.

In testimony whereof I affix my signature.

THOMAS R. BURKE. [L. s.]
